VASE FOR FLOWERS OR THE LIKE

Loyal F. Miner, Norco, Calif., assignor of a fractional part interest to Robert T. Ehninger, Huntington Beach, Calif.

Filed June 22, 1970, Ser. No. 23,581

Term of patent 14 years

Int. Cl. D11—02

U.S. Cl. D29—28

Fig. 2

Fig. 1

Fig. 3

FIG. 4

FIG. 5

FIG. 6

FIG. 1 is a front elevational view of a vase for flowers or the like embodying my new design;

FIG. 2 is a top plan view thereof;

FIG. 3 is a side elevational view thereof taken from the righthand side of FIG. 1;

FIG. 4 is a top plan view of another form of vase for flowers or the like embodying my new design;

FIG. 5 is a front elevational view thereof; and

FIG. 6 is a side elevational view thereof taken from the righthand side of FIG. 5.

The drawing has been lined for transparency.

I claim:

The ornamental design for a vase for flowers or the like, substantially as shown and described.
